FASTENINGS AND METHOD OF MAKING
THE SAME

George A. Smith, Philadelphia, Pa.

Application July 27, 1932, Serial No. 624,985

22 Claims. (Cl. 112—262)

This invention relates to fastenings and methods for their production, and more specifically to stitched fastenings for securing flexible members to elongated, substantially rigid elements; 5 for example, the fastenings are adapted to secure covers to the ribs of umbrellas.

Up to the present time, it has been customary to fasten the covers of umbrellas or parasols to the ribs, that is, to the ribs proper in the case 10 of men's umbrellas or to separate tips effectively forming parts of the ribs in the case of women's umbrellas, by hand stitching, the stitch employed being the ordinary hand or "pop" stitch. This stitching is effected by passing a threaded needle 15 successively through the cover and the eye provided either by a small loop on the rib or an opening through the separate tip, and about the inner and outer sides of the cover, the thread, usually doubled, forming, in effect, a plurality 20 of figures eight as viewed axially of the rib. This operation not only requires that the needle be manipulated by pushing to cause it to enter the eye or aperture and pulling to draw it completely through and tighten the stitch, but also necessitates a rethreading of the needle following 25 completion of each fastening preparatorily to the beginning of the next. Both the manipulation of the needle in its passages and the rethreading operations take considerable time even in the case of performance by a skilled worker.

The machines which have heretofore been devised to sew umbrella covers to the ribs make the same type of stitch and are subject to the same 30 disadvantages of requiring pushing and pulling operations upon the needles, effected by clamps which must grip and release the needles during the operations, and of requiring rethreading mechanism which must operate between stitching cycles. Both these requirements necessitate 35 the use of relatively heavy needles to prevent bending and to provide eyes large enough for practical rethreading. Furthermore, all machines of the "pop" stitch type must have means for compensating for the continuously decreasing 40 length of thread as each stitching cycle progresses and thread is used up in the fastening. The adjustment of this compensating means is quite critical and any irregularities such as the taking of too much thread by the stitch in any 45 passage, due, for example, to an abnormally thick seam in the cover, will result in breakage.

These disadvantages of the machine production of the "pop" stitch have so long been known that this stitch has been abandoned as a practical 50 sewing machine stitch except in certain em-

broidery machines which are used only to produce an imitation of a hand made stitch. In view of this the question immediately arises as to why the stitches ordinarily produced by machine sewing have not been used both in hand 5 and machine stitching of umbrella covers to ribs. An examination of the characteristics of these stitches readily answers this question: they are not adapted for use except where there is fabric existing between the successive loops passed by 10 the needles; that is, removal of fabric from between successive stitches of the lock, single chain, double chain, or various overseam stitches will result in a collapse of the stitch structures so that any holding power is lost. In the case of 15 an umbrella of conventional type, the stitches forming any single fastening will pass through the same holes in the portions of the cover on opposite sides of the rib, or at any rate, they will be separated only by very few warp or weft 20 threads which will be readily torn. Ordinary overseaming stitches, for example those produced by vibrating needle operation will also either collapse or cause interlocks in which the engaging loops tend to cut each other or become loose 25 by readjustment or slipping due to the stresses on the cover when the umbrella is opened.

It is the broad object of the present invention to provide stitches of a type avoiding the objection mentioned above; that is, the new stitches 30 are producible by the use of an eye-pointed needle which carries loops through the work but which itself is not passed entirely therethrough; the needle always remains threaded after the completion of a cycle and draws thread from a 35 spool or bobbin; and the stitches do not collapse but instead maintain their initial condition to provide a secure fastening. In the preferred 40 stitch ravelling is impossible, while in another stitch also within the scope of the invention, ravelling will not occur except under unusual 45 conditions.

Another object is the provision of methods for forming such stitches in a practical manner.

Other detailed objects will become apparent 45 from the following description read in conjunction with the accompanying drawings, in which:

Figs. 1 to 4, inclusive, are conventionalized, diagrammatic, sectional views showing successive steps involved in the formation of the preferred form of fastening;

Fig. 5 is a similar view showing the finished fastening;

Fig. 6 is a perspective diagrammatic view 55

showing the fastening alone in expanded condition to illustrate the loopings;

Fig. 7 is an axial section through a tool suitable for use in the formation of the stitch;

5 Figs. 8, 9 and 10 are conventionalized, diagrammatic, sectional views showing successive steps involved in the formation of another form of fastening within the scope of the invention;

Fig. 11 is a similar view of this form of stitch;

10 Fig. 12 is a side elevation of the same viewed in the direction of the opening through the rib tip; and

Fig. 13 is a view similar to Fig. 6 of the second form of fastening.

15 In Figs. 1 to 4, inclusive, there are illustrated the successive steps involved in the formation of the preferred type of fastening by which the rib tip 2 provided with a transverse opening 4 has secured thereto a cover 6 having a selvage or turned edge. Although the seam between triangular segments of the cover generally lies closely adjacent the rib, this seam is omitted from the drawing for clearness. While a separate tip of the type commonly used on women's umbrellas is 20 illustrated as forming the end of a rib, it will be clear that the same fastening and method are applicable to the securing of a cover to the end of any other type of rib such as that ordinarily used in men's umbrellas in which a metallic loop 25 provides an eye to receive the stitches.

The cover 6 is clamped to the tip with its outer end projecting over the opening 4 by means of members 8 which may be urged together yielding- 30 ly by a spring or may be positively held in clamp- 35 ing position.

The formation of the fastening is accom- 40 plished by the use of a needle 10 provided with an eye near its point, the point being preferably rounded rather than sharp to avoid severing during subsequent passages strands which may already lie in the opening 4. For example, the type 45 of needle commonly used in button sewing machines may be used. The needle is threaded with a thread 12 of suitable character, the thread ex- tending at 14 from the underside of the needle to a supply spool or bobbin.

In the initial passage of the needle which takes place through the portion of the cover on one side of the tip, through the opening 4, and through 50 the portion of the cover on the other side of the tip, (though it is satisfactory to pass it through the cover on one side only), care is taken that even after drawing a loop there will be sufficient 55 thread extending from the eye on the upper side of the needle to provide an end 16 which will finally project from the entrance end of the opening 4 or at least will not be drawn outwardly from the exit end.

Following a penetrating movement sufficient to 60 carry the needle eye well beyond the tip, the needle is slightly retracted to cause a loop to be formed on its upper side in the usual manner by reason of retarding friction on the upper strand of thread. This loop 18 is seized by the operator, 65 using the fingers or an instrument such as a thimble provided with a loop catching prong, widened and drawn outwardly, and passed over the end of the tip as indicated in Fig. 1. The loop 18 in this operation is produced from the 70 strand 16 extending above the needle unless this strand is held, in which case it is formed by drawing thread from the supply through the needle eye. While the loop is held, the needle is retracted as indicated in Fig. 2, the thread being 75 permitted to run through its eye, and the loop

18 is then pressed downwardly below the level of the needle path producing a depression in the strand 20, extending from the base of the loop 18 at the exit of the opening 4 to the needle eye.

Following the attainment of the conditions ex- 5 hibited in Fig. 2, the needle is again projected forwardly. Preferably, the thread is now held at the needle, for example, by a suitable tension or clamp carried by a needle holder as will be here- 10 after described, so that during the forward move- ment the thread will not run through the needle eye but will be drawn from the supply. By this action, the strand 20 is looped back upon itself as at 24 (Fig. 6) when the needle advances drawing a bight 22 from the loop 18 into the opening 15 4, and thus tightening the loop 18 about the cover. The clamping action upon the thread is prefer- 20 ably yielding so that as soon as the predetermined tightness of the loop 18 is attained, the thread may again run through the eye of the 25 needle as the needle reaches the end of its pene- trating stroke.

The needle is then again given a slight retraction to cause the throwing out of a loop 26 which is seized, looped over the end of the tip as shown in 25 Fig. 3, and depressed below the needle path as shown in Fig. 4 after the needle is again fully re- tracted. The same sequence of events is then 30 repeated until the desired number of stitches is formed which in Fig. 5 is shown as five while in 35 the diagrammatic showing of Fig. 6 it is shown as three, the bight formed in the loop 26 being indicated at 28. The last loop 30 which is thrown over the end of the tip does not have a bight 40 formed therein, this loop being drawn tight during the retraction of the needle by clamping the thread so that passage through the needle eye is prevented. Following this, the strand extending from the base of the loop 30 to the needle is 45 severed leaving an end 32 projecting from the entrance of the opening 4. Both the ends 16 and 32 may be trimmed off closely to provide a fin- 50 ished appearance.

The various loops about the cover and tip 55 are very effectively held tight by reason of the 45 bights formed therein so as to provide a fastening which will not become loose under the strains incident to the opening of the umbrella. There is no substantial strain on the last loop 30, since the other loops bind the cover quite tightly, and 50 this last loop is held sufficiently securely to prevent its accidental widening or displacement not only by the friction upon it due to its contact with the cover but also by the friction upon the strand 32 within the opening 4 and the holes in 55 the cover. The loop 30 in turn maintains the bight in the next preceding loop so that this loop is most securely held in tight condition.

It may be pointed out that the bights in the loops insure that the stitch structure will not 60 collapse even though the needle repeatedly enters the same hole. While the stitch is idealized in Fig. 6, it is not necessary that successive penetrations of the needle take place above all the strands already existing in the hole so long as 65 bights are formed in the loops to provide a non- collapsing structure. In actual practice, the needle sometimes penetrates below previously formed loops with a resulting complicated interlocking within the opening. Such fastenings are, 70 of course, within the scope of the invention.

While in the illustrated embodiment the tip is assumed secured to the rib during the fastening operation, the same stitch may obviously be used to secure the cover to a tip when separated from 75

the rib, these tips being ordinarily provided with sockets into which the rib projects. In this latter case to produce a more finished appearance, the cover may be stitched inside out to the rib in which case the end of the tip over which the loops are carried is the end having the rib-receiving socket. Following such stitching the cover is folded over the loops concealing them in a manner similar to that illustrated in the patent to

10 Scharf, Number 1,798,110, dated March 24, 1931, in which the ordinary "pop" stitch provides the fastening.

In Fig. 7 there is illustrated a suitable instrument for the formation of stitches in accordance with the invention. This comprises a handle 34 of convenient shape provided with a socket for the reception of the shank of the needle 10. A plate 36 carried by the handle is provided with outwardly turned ends perforated to furnish 20 thread guiding eyes. Extending across the outer surface of plate 36 and arranged to clamp the thread 12 against the plate is a cross member 38 carried by a plunger 40 which is urged to the right as viewed in Fig. 7 by a compression spring 25 44 reacting between the plate 36 and a head 42 carried by the plunger. The clamping tension imposed upon the thread under the action of the spring 44 may be relieved by the pressure of the thumb of the operator upon the head 42. 30 When free running of the thread through the eye of the needle is desired, the tension is relieved by thumb pressure. On the other hand when clamping is required as indicated above in the formation of the bights 22, 28 or the tightening 35 of the final loop 30, the spring 44 is freed to provide the necessary tension. The spring 44 is preferably of such character that, although ample tension will be imparted to the thread when desired, the thread will run between 36 and 38 40 and through the needle eye without breaking if sufficient thread to accommodate needle movements is not available on the upper side of the needle.

It will be clear from the above description that 45 there is provided a fastening adapted for umbrellas, parasols or the like which avoids the time consuming operations necessitated by the use of the ordinary "pop" stitch, but which will hold the cover securely to the rib.

50 Referring now to Figs. 8 to 13, inclusive, there is illustrated therein a modified form of fastening within the scope of the invention. In the formation of this fastening, the loop 50, which is formed from the upper strand 16 of the thread 55 12 after the initial penetrating movement of the needle upon its loop forming retraction, is drawn about the cover as shown in Fig. 8, and then positioned as in Fig. 9, after retraction of the needle, so that the needle upon its subsequent forward movement will enter the loop. As it moves inwardly, the strand 52 extending from the base of the loop 50 at the exit of the opening 4 is doubled back upon itself so that the end 54 of the loop 50 is drawn into the opening 60 65 and the loop is thereby drawn tightly about the cover, this result being accomplished in the same manner as the formation of the bight 22 in the previous modification by prevention of running of the thread through the eye as the needle advances, for example by the use of the instrument of Fig. 7. The next loop 56 is similarly drawn and subsequent operations proceed in corresponding fashion to form loops 58 and 60. The final operation is the passage of the needle through the last 70 75 loop 60 whereupon the thread is severed leaving

an end 62 projecting from the exit of the opening 4. The needle, of course, remains threaded, the severing taking place through the loop thrown out on the upper side of the needle following the last penetration.

5 Figs. 11 and 12 illustrate a fastening comprising three loops but involving four needle penetrations. A fastening having four loops is shown in Fig. 13.

In this second modification, all of the loops may 10 be carried about the outside of the cover, as illustrated, about the inside of the tip, or alternately about the outside and inside. As in the case of the first modification, the showing of Fig. 13 is idealized and actually there is usually considerably more complication within the opening 4. In this case, also, the fastening of the cover inside out to the tip may be produced. Further, the cover need only be penetrated on one side of the tip.

20 It will be noted that the ends 16 and 62 extend oppositely from the opening 4. This is necessary in this modification since the stitch is of a chain type and raveling would otherwise occur. The drawing of the loops within the opening is important in that a frictional holding is produced avoiding loosening of the stitches.

25 Both forms of fastenings herein illustrated may be briefly stated to consist of at least two loops formed in a single length of thread and penetrating the cover, the loops extending from one end of the opening 4 about the cover and tip and one having a portion extending into the other end of the opening and anchoring therein the thread between the loops. In the preferred modification 30 the loops not only extend about the tip and cover but actually encircle them. The improved fastening and method are, of course, applicable for other purposes than the securing of umbrella or parasol covers. Furthermore, variations within 35 the scope of the invention as defined in the claims will be apparent to those skilled in the art.

40 What is claimed is:

1. In combination, an elongated rigid element 45 having a thread receiving opening therein, a flexible member, and stitching extending through the member and said opening to secure the member to the element, said stitching consisting of a length of thread formed into at least two loops extending outwardly from one end of said opening about said member and element, one of the loops having a portion extending into the other end of the opening and anchoring therein the thread between said loops.

50 2. In combination, an elongated rigid element 55 having a thread receiving opening therein, a flexible member, and stitching extending through the member and said opening to secure the member to the element, said stitching consisting of a length of thread formed into at least two loops 60 extending outwardly from one end of said opening, each loop comprising a section of the thread doubled on itself to form an open eye receiving the member and element.

65 3. In combination, an elongated rigid element 65 having a thread receiving opening therein, a flexible member, and stitching extending through the member and said opening to secure the member to the element, said stitching consisting of a length of thread formed into at least two loops 70 extending outwardly from one end of said opening, each loop comprising a section of the thread doubled on itself to form an open eye receiving the member and element, and one of said loops anchoring the thread between the loops.

4. In combination, an elongated rigid element having a thread receiving opening therein, a flexible member, and stitching extending through the member and said opening to secure the member to the element, said stitching consisting of a length of thread formed into at least two loops extending outwardly from one end of said opening, each loop comprising a section of the thread doubled on itself to form an open eye receiving the member and element, and one of said loops anchoring the thread between the loops at the other end of said opening.
5. In combination, an elongated rigid element having a thread receiving opening therein, a flexible member, and stitching extending through the member and said opening to secure the member to the element, said stitching consisting of a length of thread formed into at least two loops extending outwardly from one end of said opening, each loop comprising a section of the thread doubled on itself to form an eye receiving the member and element and one of the loops having a portion extending into the other end of the opening and anchoring therein the thread between the loops.
6. In combination, an elongated rigid element having a thread receiving opening therein, a flexible member, and stitching extending through the member and said opening to secure the member to the element, said stitching including a length of thread formed into a plurality of loops extending outwardly from one end of said opening, each loop comprising a section of the thread doubled on itself to form an eye receiving the member and element, the thread between the loops being anchored within said opening.
7. In combination, an elongated rigid element having a thread receiving opening therein, a flexible member, and stitching extending through the member and said opening to secure the member to the element, said stitching consisting of a length of thread formed into at least two loops each of which comprises a section of the thread doubled on itself with both sides extending outwardly from one end of said opening about a side of the element, one of the loops having a portion extending into the other end of the opening and anchoring therein the thread between the loops.
8. The method of securing a flexible member to an elongated rigid element having a thread receiving opening therein by a thread extending through the eye of a needle from a supply including passing a loop of thread through the member and opening by a passage of the threaded needle, drawing the loop from the exit end of the opening about the member and element, and passing a second loop of the thread through the member and opening by a passage of the threaded needle in the same direction as the first loop in such manner as to cause the thread between the loops to engage an intermediate portion of the first loop to be anchored thereby.
9. The method of securing a flexible member to an elongated rigid element having a thread receiving opening therein by a thread extending through the eye of a needle from a supply including passing a loop of thread through the member and opening by a passage of the threaded needle, drawing the loop from the exit end of the opening about the member and element, and passing a second loop of the thread through the member and opening in the same direction as the first loop in such manner as to cause the thread between the loops to draw into the entrance end of the opening an intermediate portion of the first loop to be anchored thereby.
10. The method of securing a flexible member to an elongated rigid element having a thread receiving opening therein by a thread extending through the eye of a needle from a supply including passing a loop of thread through the member and opening by a passage of the threaded needle, drawing the loop from the exit end of the opening over an end of the element to encircle the same, and passing a second loop of the thread through the member and opening in the same direction as the first loop in such manner as to cause the thread between the loops to engage an intermediate portion of the first loop to be anchored thereby.
11. The method of securing a flexible member to an elongated rigid element having a thread receiving opening therein by a thread extending through the eye of a needle from a supply including passing a loop of thread through the member and opening by a passage of the threaded needle, drawing the loop from the exit end of the opening over an end of the element to encircle the same, and passing a second loop of the thread through the member and opening in the same direction as the first loop in such manner as to cause the thread between the loops to draw into the entrance end of the opening an intermediate portion of the first loop to be anchored thereby.
12. The method of securing a flexible member to an elongated rigid element having a thread receiving opening therein by a thread extending through the eye of a needle from a supply including passing a loop of thread through the member and opening by a passage of the threaded needle, drawing the loop from the exit end of the opening about the member and element at one side thereof, and passing a second loop of the thread through the member and opening by a passage of the threaded needle in the same direction as the first loop in such manner as to cause the thread between the loops to engage an intermediate portion of the first loop to be anchored thereby.
13. The method of securing a flexible member to an elongated rigid element having a thread receiving opening therein including passing a loop of thread through the member and opening, drawing the loop from the exit end of the opening about the member and element at one side thereof, and passing a second loop of the thread through the member and opening in the same direction as the first loop in such manner as to cause the thread between the loops to draw into the entrance end of the opening an intermediate portion of the first loop to be anchored thereby.
14. The method of stitching work adjacent an end thereof including passing a loop of thread therethrough, drawing the projecting loop over the end of the work to encircle the same, and passing a second loop of the thread through the work at substantially the position of the first passage and in the same direction in such manner as to cause the thread between the loops to engage the encircling portion of the first loop to be anchored thereby.
15. The method of stitching work adjacent an end thereof including passing a loop of thread therethrough, drawing the projecting loop over the end of the work to encircle the same, and passing a second loop of the thread through the work at substantially the position of the first

passage and in the same direction in such manner as to cause the thread between the loops to draw into the work a part of the encircling portion of the first loop to be anchored thereby.

5 16. In combination, an elongated rigid element having a thread receiving opening therein, a flexible member, and stitching extending through the member and said opening to secure the member to the element, said stitching consisting of a 10 length of thread formed into at least two loops extending outwardly from one end of said opening about said member and element, each of said loops comprising a section of the thread doubled on itself whereby the ends of the section are 15 located at said end of the opening, one of the loops having an intermediate portion anchoring the thread between said loops at the other end of the opening.

17. In combination, an elongated rigid element 20 having a thread receiving opening therein, a flexible member, and stitching extending through the member and said opening to secure the member to the element, said stitching consisting of a length of thread formed into at least two loops 25 each of which comprises a section of the thread doubled on itself with both sides extending outwardly from one end of said opening about one side of the element, one of said loops extending through the other at the other end of the opening whereby the latter has an intermediate portion 30 anchoring the thread between the loops at said other end of the opening.

18. The method of securing a flexible member to an elongated rigid element having a thread 35 receiving opening therein by a thread extending through the eye of a needle from a supply including passing a loop of thread through the member and opening by a passage of the threaded needle, drawing the loop from the exit end 40 of the opening over an end of the element to encircle the same, and passing a second loop of the thread through the member and opening in the same direction as the first loop by a passage of the threaded needle in such manner as to cause 45 the thread between the loops to engage an intermediate portion of the first loop to be anchored thereby.

19. The method of securing a flexible member to an elongated rigid element having a thread 50 receiving opening therein by a thread extending through the eye of a needle from a supply including passing a loop of thread through the member and opening by a passage of the threaded needle, drawing the loop from the exit end 55 of the opening over an end of the element to encircle the same, and passing a second loop of the thread through the member and opening in the same direction as the first loop by a passage of the threaded needle between the encircling portion of the first loop and said end of the 60 element while restraining the feed of thread in such manner as to cause the thread between the

loops to engage an intermediate portion of the first loop to be anchored thereby, and to draw the first loop tightly about the member and element.

20. The method of securing a flexible member 5 to an elongated rigid element having a thread receiving opening therein by a thread extending through the eye of a needle from a supply including passing a loop of thread through the member and opening by a passage of the threaded 10 needle, drawing the loop from the exit end of the opening over an end of the element to encircle the same, and passing a second loop of the thread through the member and opening in the same direction as the first loop by a passage 15 of the threaded needle between the encircling portion of the first loop and said end of the element while clamping the thread in such manner as to cause the thread between the loops to engage an intermediate portion of the first loop 20 to be anchored thereby, and to draw the first loop tightly about the member and element.

21. The method of securing a flexible member 25 to an elongated rigid element having a thread receiving opening therein by a thread extending through the eye of a needle from a supply including passing a loop of thread through the member and opening by a passage of the threaded needle, drawing the loop from the exit end of the opening over an end of the element to encircle the same, and passing a second loop of the thread through the member and opening in the same direction as the first loop by a passage 30 of the threaded needle between the encircling portion of the first loop and said end of the element while restraining the feed of thread in such manner as to cause the thread between the loops to draw into the entrance end of the opening an intermediate portion of the first loop to be anchored thereby, and to draw the first loop tightly 35 about the member and element.

22. The method of securing a flexible member 40 to an elongated rigid element having a thread receiving opening therein by a thread extending through the eye of a needle from a supply including passing a loop of thread through the member and opening by a passage of the threaded needle, drawing the loop from the exit end of the opening over an end of the element to encircle the same, and passing a second loop of 45 the thread through the member and opening in the same direction as the first loop by a passage of the threaded needle between the encircling portion of the first loop and said end of the element while clamping the thread in such manner as to cause the thread between the loops to draw into the entrance end of the opening an intermediate portion of the first loop to be anchored thereby, and to draw the first loop tightly 50 about the member and element.
